UNITED STATES PATENT OFFICE.

WILLIAM R. JEAVONS, OF CLEVELAND, OHIO.

OIL-STOVE.

No. 908,997.

Specification of Letters Patent.

Patented Jan. 5, 1909.

Application filed May 2, 1908. Serial No. 430,432.

To all whom it may concern:

Be it known that I, WILLIAM R. JEAVONS, a citizen of the United States, residing at Cleveland, in the county of Cuyahoga and State of Ohio, have invented a certain new and useful Improvement in Oil-Stoves, of which the following is a full, clear, and exact description, reference being had to the accompanying drawings.

10 This invention relates to oil stoves and more especially to that class having burners wherein a blue flame is produced from a wick without the provision of perforated commingling tubes.

15 The general object of the invention is to improve the efficiency of such burners.

More specifically stated, the object of the invention is to provide effective means whereby the disagreeable humming noise 20 produced by the vibrations or fluctuations of air about the flame may be avoided.

Generally speaking, the invention may be defined as consisting of the combinations of elements embodied in the claims hereto annexed and illustrated in the drawings forming a part hereof, wherein

Figure 1 represents a vertical sectional view taken through a burner constructed in accordance with my invention, a portion of 30 the supply pipe and the air distributor locking means being shown in elevation; Fig. 2 represents a view, partly in section and partly in elevation, of a modification of the invention shown in Fig. 1; and Fig. 3 represents a sectional detail on the line 3--3 of Fig. 1.

In my Patent No. 848,828, issued April 2nd, 1907, I have disclosed one means for preventing the disagreeable humming noise 40 which is liable to occur in blue flame burners of the type wherein the blue flame is produced from a wick without the employment of perforated commingling tubes. The construction disclosed in said patent effectively 45 prevents the humming noise referred to, under certain conditions. Under adverse conditions of wick and air supply, however, the construction shown in the patent will not always prevent the disagreeable noise referred to. I have found that, by extending the upper portion of the collar to form a shield, the air stratum which is supplied between the collar and the outer wick tube is caused to flow evenly and steadily alongside 55 of the outer portion of the flame and hold the

flame smoothly yet rigidly in constant shape, so that extremely adverse conditions, such as the unequal air currents or the formation of strong air eddies within the outer drum or chimney will not affect the smoothness of this air stratum and thus the vibrations in the flame referred to which are the cause of the disagreeable humming noise are prevented.

With the type of burner illustrated herein, the full operative height of the wick is substantially midway between the plane of the top of the outer wick tube and the plane of the lower outer edge of the spreader; the normal excursion of the wick is from below this midway position to about such midway position. I have found that by constructing the collar which surrounds the outer wick tube in such manner that it is provided with a relatively narrow or restricted portion about midway between the top of the wick tube and the bottom of the outer edge of the spreader and by providing such collar with a relatively smooth throat or interior therebelow and by providing the collar with an outwardly flaring portion above such restricted portion, I am able to overcome the objectionable noise referred to. This construction delivers the air in a smooth, strong, even current through the throat of the collar and alongside of the flame above the throat, without the production of air eddies, which would destroy the smoothness of such flow. The lack of rigidity and smoothness of such air flow would contribute to the conditions which produce the objectionable humming noise of the flame. To obtain the best results, the contour of the flared portion of the collar above the restricted portion or throat should be such as to maintain between itself and the flame an air passage of substantially constant width, as such construction better avoids the formation of eddies in the air stratum above the restricted portion of the collar. Furthermore, by extending the collar above the restricted portion thereof nearly to the full operative height of the flame, the body portion of the flame is protected from eddies and any other air disturbances that may exist within the drum. The restricted or throat portion of the collar must not be so high as to prevent a slight outward drift or flattening of the flame by the air which is discharged under the spreader from the interior of the wick

tube. This air current from under the spreader tends in a more or less degree to direct the flame outwardly over the air current rising through the collar and this outward drift or direction of the burning vapors more surely insures the production of a blue flame. The best results are produced by extending the top of the collar to a point somewhat above the lower edge of the spreader, as this shields nearly all of the body portion of a maximum flame from eddies and other air disturbances within the drum.

Describing the parts by reference numerals, 1 denotes the outer and 2 the inner wick tube of a burner. 3 denotes the wick within said tubes, said wick being provided with a carrier 4 adapted to be engaged by the star wheel 5 on an inclined shaft 6.

7 denotes the outer ring of a centering device for the spreader, and 8 inwardly projecting arms having at their inner ends a ring 9 for the spindle 10 which carries the air deflector. This air deflector comprises a frusto-conical perforated ring 11 secured at its upper end to the spreader 12, as by means of a suitable number of eyelets 13. The ring 11 and spreader 12 are secured to the upper end of spindle 10.

14 denotes an upwardly projecting ring which is secured at its lower end to the vertical skirt 15 of ring 11. Ring 14 is of sufficiently less external diameter than the internal diameter of wick tube 2 to enable it to be freely and removably fitted therewith and to provide a space therewith. The upper end of this ring is flared or bent inwardly, as shown at 16, the base of the flared portion being formed by a knee or bend in substantially the same plane as the upper end of wick tube 1. The ring 14 will be provided with perforations 17 which may be located both above and below said knee or bend. The inwardly flaring portion 16 provides an air barrier to protect the inside of the wick from the rapid air flow and to provide for the rapid flow of air above the wick, the top of said barrier being in substantially the same plane as the top of the wick when the latter is raised to full operative height, namely, about midway between the top of the outer wick tube and the lower outer edge of spreader 12.

The outer wick tube is provided with a ledge 18, which may be conveniently formed by bending the metal thereof outwardly, which ledge constitutes a seat for the collar 19. This collar is provided with a suitable number of inwardly extending projections or supports 19^a which are adapted to engage ledge 18 and support the collar in operative relation to the burner. The lower end of the collar comprises an outwardly flared skirt 20 depending from the horizontal ledge 21 which forms a support for the inwardly curved lower end 22 of the drum or chimney

23. The inwardly projecting portion 22 may be, and preferably is, provided with a number of perforations 24 for the admission of a measure of air to the base of the drum outside of the collar, as this tends to keep the drum walls cooler. The collar 19 extends upwardly from ledge 21 to a point below the top of the outer wick tube, whence it projects inwardly toward a point above the top of the wick tube and thence flares outwardly, the upper edge of the collar extending somewhat above the lower edge of the spreader. The upper end of the collar is preferably formed by bending the same in the manner shown in Fig. 1; that is to say, so that the inner surface of said collar projects inwardly to a plane about midway between the top of the outer wick tube and the lower edge of the spreader and thence projects outwardly, the upper edge of said collar being above the lower edge of the spreader, and it is desirable that the inner surface of the collar be substantially smooth and unbroken, particularly from the throat or most restricted portion 19^b thereof downwardly at least as far as the top of the outer wick tube. By reference to Fig. 1, it will be seen that the location of the outwardly flaring portion of the collar does not prevent the spreading of the flame 25 by the air supplied from the interior of the burner and that a relatively smooth throat or interior is provided for the supply of the air in a smooth even current to the exterior of the flame and that the contour of the flared portion 19^c of this collar is such as to maintain between itself and the flame an air passage of substantially constant width, whereby eddies above the contracted portion are prevented.

In Fig. 2, I have shown a modification of the collar 19. In this modification, 26 denotes the body of the collar which is similar to the lower portion of collar 19 and is provided with inwardly extending projections 27 engaging the ledge 18 on the outer wick tube. The body 26 extends in a vertical direction from the ledge 26^a to about the same distance as the vertically projecting portion of 19, whence it is bent inwardly, as shown at 29. At the base of the inwardly bent portion 29 there is provided a ledge 30 which supports the lower inturned end 31 of an outwardly flaring collar 32. The upper edge of 29, which forms the throat portion, is in substantially the same plane as the most restricted portion 19^b of the collar 19 and the upper edge of 32 occupies the same position with reference to the flame and the spreader as does the upper edge of 19^c. The function and mode of operation of the collar shown in Fig. 2 is the same, or substantially the same, as the function and mode of operation of the collar shown in Fig. 1.

33^a denotes the supply pipe, through which oil is supplied to the burner, and 34 a hook

soldered to the inner wick tube and engaging the supply pipe in the same manner as described in my Patent No. 848,828.

33 denotes a tubular connection projecting from the outer wick tube at a point opposite the hook 34. The tube 33 projects downwardly at its outer end, as shown at 35. The lower end of 35 is reduced somewhat, as shown at 35^a, so as to fit within the sleeve 36. 10 This sleeve forms part of the detachable connection between the burner and the supply pipe.

37 denotes a washer of compressible and more or less plastic material, which is 15 mounted within sleeve 36 and has a central perforation therethrough for a nipple 38. The lower end of sleeve 36 projects inwardly, to provide an annular flange 39. The internal diameter of this flange is considerably 20 greater than the external diameter of nipple 38. The upper end of this nipple projects above the washer 37 and is preferably provided with a ledge 40, by which it will rest upon the top of the washer. The upwardly 25 extending end of nipple 38 is adapted to enter the bore of the tubular connection 33 to pilot the same to central position on washer 37. The supply pipe may be provided with a recess 41, providing a flat-seat 30 for the ledge 39, and is provided with an aperture, preferably threaded, for the reception of the threaded lower end of nipple 38.

To secure the parts described to the supply pipe, I preferably employ a strap consisting 35 of two side members 42 and 43, which may be connected at their outturned lower ends by means of a loop 44 applied thereto, as shown in Fig. 3. Through the upper end of the strap there extends a short bolt 45, the 40 lower pointed end whereof engages a seat at the top of connection 33. A nut 46 is fitted within the upper portion of the strap and receives the bolt 45. This nut is held against rotation by the strap whereby, on 45 rotating the bolt, the strap may be loosened or tightened.

As previously stated, washer 37 is of material which will be compressed by tightening the bolt 45. The material which I 50 preferably employ for this purpose is lead. On tightening up on bolt 45, this lead is compressed and is squeezed through the annular space between flange 39 and nipple 38 to the seat which supports the flange, also upwardly between the sleeve and the reduced lower end 35^a of connection 33 and between the nipple 38 and such end. This construction provides an extremely efficient form of connection between the supply pipe and the 55 burner. It is not necessary to take any special pains to provide a smooth seat in recess 41 for the connection, as the lead will accommodate itself to any irregularities of surface. Furthermore, the manner in which the lead 60 flows, under compression, around the outside 65

and the inside of the reduced lower end 35^a, insures a tight joint at this place. A great advantage in this construction resides in the fact that it dispenses with the use of a soldered joint, enabling the pipe to be tinned 70 and lacquered before connecting the burner thereto, without producing the discoloration of the tin and lacquer coating on the pipe which would result from soldering the burner connection thereto. 75

At the end of the pipe, I use a detachable plug which embodies the same principles as the connection hereinbefore described. This plug comprises a body 47 having a base 48 from which there projects the threaded plug 80 proper 49.

50 denotes a washer which is of such internal diameter as to be adjusted along the plug 49.

51 denotes a sleeve having an inwardly 85 projecting flange 52 which is of greater internal diameter than the external diameter of 49. This sleeve is of greater length than the depth of said washer and is of slightly greater diameter than the end of the supply 90 pipe 33. In using my plug, the end 49 is threaded into the supply pipe and is set up firmly thereagainst. This compresses the washer, which is preferably of lead, squeezing some of the material thereof through the 95 annular space between flange 52 and the unthreaded portion 53 of said plug to the seat which supports the flange 52 and also squeezing some of the washer material into the space between the outer end of the flange 100 and the supply pipe. The construction described provides simple but very effective means for forming a tight but detachable closure for the end of the supply pipe and prevents the plug from jarring out in shipment. To facilitate the adjustment of the plug, the outer end thereof is provided with an aperture 54 for the application of a rod or other adjusting means thereto. The construction of the joints or connections formed 105 between the burner and the supply pipe and between the plug 47 and the supply pipe constitutes the subject matter of my application No. 462,775, filed November 16th, 1908.

For the purpose of automatically locking 115 the spreader and the associated parts in position by the act of inserting the spreader and such parts into the upper part of the inner wick tube, the air distributor may be provided with an automatic locking device 120 55 adapted to engage the arms 8, as shown, described and claimed in my Patent No. 871,593, issued Nov. 19th, 1907.

Having thus described my invention, I 125 claim:

1. In an oil burner, the combination of inner and outer wick tubes, a spreader extending above the upper end of said tubes and spaced therefrom, a vertically extending ring within and spaced from the inner wick 130

1 tube and forming an air barrier for the inside of the wick, and a collar surrounding the upper end of the outer wick tube and extending upward to the plane of the spreader, said 5 collar being contracted in diameter at a point between the tops of the wick tubes and the spreader.

2. In an oil burner, the combination of inner and outer wick tubes, a spreader extending above the upper end of said tubes and spaced therefrom, a vertically extending ring within and spaced from the inner wick tube and forming an air barrier for the inside of the wick, and a collar surrounding the upper end of the outer wick tube, said collar being contracted in diameter at a point between the tops of the wick tubes and the spreader and being of larger diameter above such contracted portion.

20 3. In an oil burner, the combination of inner and outer wick tubes, a spreader extending above the tops of said tubes, an air barrier within the inner tube and extending above the top of the same, and a collar 25 circumscribing the upper end of the outer wick tube and projecting upward to a point as high as the lower edge of the spreader, said collar forming a smooth unbroken passageway about the top of the outer wick tube for 30 the supply of air therethrough and being of larger diameter above the top of the plane of the air barrier.

4. In an oil burner, the combination of inner and outer wick tubes, a spreader extending 35 above the tops of said tubes, an air barrier within said tubes and extending above the tops of the same, and a collar circumscribing the upper portion of the outer wick tube and projecting upward to a point above 40 the lower edge of the spreader, said collar forming a smooth, unbroken passageway about the top of the outer wick tube for the supply of air therethrough and being of larger diameter above the plane of the top of 45 the air barrier.

5. In an oil burner, the combination of inner and outer wick tubes, a spreader extending above the tops of said tubes and spaced therefrom, a ring within the inner wick tube 50 and projecting upwardly to a plane between the top of the wick tubes and the bottom of the spreader to form an air barrier for the in-

ner surface of the wick, and a collar surrounding the upper portion of the outer wick tube and having an inwardly projecting 55 portion with an outwardly projecting portion thereabove, the smallest diameter of said collar being in a plane between the top of the outer wick tube and the bottom of the spreader.

6. In an oil burner, the combination of inner and outer wick tubes, a spreader extending above the tops of said tubes and spaced therefrom, a ring within the inner wick tube and projecting upwardly about midway between the top of the wick tubes and the bottom of the spreader to form an air barrier for the inner surface of the wick, and a collar surrounding the upper portion of the outer wick tube and having an inwardly projecting 65 portion with an outwardly projecting portion thereabove, the smallest diameter of said collar being in a plane substantially midway between the top of the outer wick tube and the bottom of the spreader.

7. In an oil burner, the combination of inner and outer wick tubes, a spreader extending above the upper ends of said tubes and spaced therefrom, a collar surrounding the upper end of the outer wick tube and spaced 70 therefrom, said collar having its upper end flared outwardly, such flared portion extending above the outer edge of the spreader, and a vertically extending ring within and spaced from the inner wick tube and forming an air 75 barrier for the inside of the wick.

8. In an oil burner, the combination of inner and outer wick tubes, a spreader extending above the upper ends of said tubes and spaced therefrom, a collar surrounding the upper end of the outer wick tubes and spaced 80 therefrom, said collar having its upper end portion flared outwardly and such outwardly flaring portion extending above the outer edge of the spreader, and a vertically extending ring within the inner wick tube and forming an air barrier for the inside 85 of the wick.

9. In testimony whereof, I hereunto affix my signature in the presence of two witnesses. 100

WILLIAM R. JEAVONS.
